UNITED STATES PATENT OFFICE.

GIUSEPPE GARBUIO, OF TREVISO, ITALY.

DRYING APPARATUS FOR THE DRYING OF ALIMENTARY PASTE.

Application filed April 26, 1926, Serial No. 104,818, and in Italy November 7, 1925.

- This invention relates to improved drying apparatus such as is employed for the drying of alimentary paste, macaroni and similar pastes for example.
- 5 One object of the invention is to provide an apparatus in which the drying is carried out under uniform conditions over long periods in spite of external atmospheric changes.
- 10 A further object is to provide a drier in which there is a limited introduction of external air and a limited drawing off of humidified air, the remainder of the humidified air being circulated and mixed with the air 15 newly introduced.
- A further object is to provide apparatus of simple construction adapted for enabling the relative proportions of the air volumes to be varied in accordance with requirements.
- 20 These and other objects are attained by apparatus exemplified in the annexed drawing, in which:—
- Figure 1 is a front elevation.
- Figures 2 and 3 are vertical sections taken 25 in planes at right angles to one another.
- Figures 4 and 5 show respectively, on a larger scale, the means for attaching and varying the blades of the ventilators, and a regulator arrangement for varying the quantity of air admitted to a drier fitted with non-variable flap-valves.
- Figs. 6 and 7 are a plan view and bottom plan view respectively of the blades of a ventilator, drawn on a larger scale.
- 35 Figs. 8 and 9 are a perspective view and a front elevation respectively of the ventilator in closed position.
- Fig. 10 is a front elevation of the ventilator in open position.
- 40 The drier comprises a central shaft 1 upon which are mounted the fans or ventilators 2, 3, 4, and 5, the shaft being driven by a suitable transmission and pulley 6 keyed to the end of the shaft. According to one construction, the ventilators or fans 2 and 5 mounted near to respective ends of the shaft 1 comprise adjustable blades adapted for having their pitch varied under control of suitable mechanism. For example, such 45 mechanism may comprise rods 7 and 8 connected with a ring 9 which, in turn, is connected by a rod 10 having its free end connected with a ring 11. The latter is displaceable along the shaft by means of the 50 control lever 12, Figures 2 and 3. The intermediate fans 3 and 4 are of greater diameter than the fans 2 and 5, and the air entry is of constant cross sectional area.
- According to the alternative construction and arrangement, the air entry is variable by 60 means of valves 13 and 14, which regulate the passage of the air as seen in Figure 5.
- In both cases, the fan 2 sucks air from the chamber wherein the drier is installed, that is to say pure air at constant temperature, 65 and forces this air into the upper compartment 15. The fan 3 of greater diameter than the fan 2 sucks air from the compartment 15 and distributes it uniformly in all directions for traversing the mass of paste 70 placed in the central compartment 16. The fan 4 withdraws the air that has passed over the paste and has become humid, and delivers it to the entry compartment, or to an intermediate space from which such air 75 passes into the compartment 15.
- It will be seen that a mixing takes place in the compartment 15 between the fresh air sucked in by the fan 2 and the humid air circulated by the fan 4. Thus, the fan 3 80 sucks in from the compartment 15 a mixture, the nature of which can be determined by suitable adjustments, and delivers such mixture to the drying compartment. At the same time, the fan 5 withdraws from the 85 interior and delivers to the exterior a certain proportion of the humid air, and the volume withdrawn by this fan will correspond with that introduced by the fan 2.
- As shown in Figs. 6, 7, 8, 9 and 10, the 90 four blades 2 or 5 of the ventilator are rotatable around the diametral pivots 20, mounted on the sleeve 21, which is rigid with the shaft 1, and each of said blades bears on its lower side the hooks 22 supporting the 95 ring 9 by means of members 7 and 8. The ring 9 is rigidly connected with the driving rods 10 which pass through the guide collar 24, which is fixed to the shaft 1, and are attached to the driving collar 11 of the blades 100 2 or 5 by means of the pressure screws 25. The opening of the blades 2 or 5 of the ventilator is regulated by displacing the lever 12, which, as it is connected with the collar 11, constrains the latter to follow it 105 in its movements.
- By operating in the manner described the drying is performed at a temperature which is approximately constant and is not marred by sudden changes. If a hot wind should 110

spring up, for example, the hot air in the chamber in which the drier is situated does not adversely affect the drying when drawn in and delivered by the fan 2. The reason for this is that such air mixes in the chamber 15 with the air already circulating in the interior as aforesaid so that it becomes dry progressively. Such air after passing into the compartment 17 leaves the paste 10 with its yellowish colour and porous surface. In this way, the paste can remain unaffected by any rise of temperature.

With a drier operating in accordance with these improvements, it is possible to dry 15 all kinds of pastes and the operation can take place even in the same period of time whilst conditions of humidity and of temperature vary in the chamber in which the apparatus is situated. This is achieved by 20 the ability to vary the volume of air introduced into and collected in the apparatus in a unit of time, that is to say the rate of renewal of the air. The energy necessary for the drying of up to 1,500 kilos is about 25 one horse power and from 1,500 to 2,000 kilos it is about two horse power. For a paste formation of small thickness a drying period of 30 hours may be required and for a paste formation of maximum thickness 30 96 hours may be necessary.

The details of construction, dimensions and so on can obviously be varied to suit particular requirements without departing from the invention as defined by the claims.

35 I claim:—

1. Drying apparatus comprising a series of simultaneously driven coaxial air propellers some of which are adapted for passing air through the drier, whilst others are 40 adapted for circulating air within the apparatus so that an admixture of incoming fresh air with circulating humid air takes place substantially as and for the purpose set forth.

45 2. Drying apparatus comprising a series of simultaneously driven air propellers, an entry compartment, a drying compartment, and a return duct connected between the exhaust from said drying compartment and 50 said entry compartment, one of said fans operating at the admission to said entry compartment, another at an opening communicating between said entry and drying compartments, another at the exhaust from 55 said drying compartment, and another between the said return duct and atmosphere

substantially as and for the purpose set forth.

3. Drying apparatus comprising a drying chamber, an air entry chamber communicating with one end of said drying chamber, an air exit chamber communicating with the opposite end of said drying chamber, a return duct communicating between said entry and exit chambers, a fan adapted for 65 charging said entry chamber with atmospheric air and a fan adapted for discharging from said exit chamber to atmosphere, and fans of greater capacity than those aforesaid disposed respectively at the air entry 70 and air exit of said drying chamber substantially as and for the purpose set forth.

4. Drying apparatus comprising a series of four fans spaced apart along a single shaft, a series of three compartments, the 75 middle one being a drying compartment, and a duct communicating between the end compartments, the end fans being disposed in apertures in outer end walls of the end compartments and the intermediate fans being disposed in respective end walls of said drying compartment substantially as set forth.

5. Drying apparatus comprising a series of four fans spaced apart along a single 85 shaft, the two end fans being similar to one another and of smaller diameter than the end fans which also are similar to one another, a series of three compartments, the middle one being a drying compartment, 90 and a duct communicating between the end compartments, the end fans being disposed in apertures in outer end walls of the end compartments and the intermediate fans being disposed in respective end walls of said 95 drying compartment substantially as set forth.

6. Drying apparatus comprising a series of four fans, a series of three compartments, the middle one being a drying compartment, 100 means of communication between said end compartments, and means for adjusting the useful effect of the first and last of said fans, said first fan being disposed for forcing atmospheric air into the first compartment 105 and said last fan being disposed for drawing air from the last compartment, the other fans being adapted for propelling within the apparatus a volume of air greater than the volume of air propelled by said first 110 and last fans substantially as set forth.

GIUSEPPE GARBUIO.
